UNITED STATES PATENT OFFICE.

CHARLES EMIL LARSEN, OF CHICAGO, ILLINOIS.

MARKING-MACHINE.

1,372,966.

Specification of Letters Patent. Patented Mar. 29, 1921.

Application filed May 28, 1920. Serial No. 384,888.

To all whom it may concern:

Be it known that I, CHARLES E. LARSEN, a citizen of the United States, and a resident of Chicago, in the county of Cook and 5 State of Illinois, have invented a new and useful Improvement in Marking-Machines, of which the following is a full, clear, and exact description.

My invention relates to a machine for 10 marking cloth or the like, and it consists in the combinations, constructions, and arrangements herein described and claimed.

An object of my invention is to provide 15 a device having means for accurately, expeditiously, and effectively marking a desired pattern upon cloth, or the like, whereby by a great saving of time and labor results.

A further object of my invention is to provide 20 a device of the type described in which means is provided for changing the pattern at will.

A further object of my invention is to provide 25 a device of the type described that is relatively simple in construction and operation and not likely to get out of order easily.

A further object of my invention is to provide 30 a device of the type described that can be operated manually.

A further object of my invention is to provide 35 a device of the type described that is thoroughly practical commercially.

Other objects and advantages will appear 40 in the following specification, and the novel features of the invention will be particularly pointed out in the appended claims.

My invention is illustrated in the accompanying drawings, forming part of this application, in which—

Figure 1 is a plan view of the device, a portion being broken away for clearance.

Fig. 2 is a side view of the device, a portion being broken away and portions being shown in section,

Fig. 3 is a section along the line 3—3 of Fig. 1,

Fig. 4 is a section along the line 4—4 of Fig. 1,

Fig. 5 is a detailed plan view of a portion 50 of the device, a portion of the same being broken away and other portions being shown in section,

Fig. 6 is a plan view of a portion of the device,

Fig. 7 is a view of the reverse side of the portion of the device shown in Fig. 6,

Fig. 8 is a view showing details of construction of the portion of the device shown in Fig. 6,

Fig. 9 is a section along the line 9—9 of Fig. 5,

Fig. 10 is a section along the line 10—10 of Fig. 5,

Fig. 11 is an enlarged section through a fragmentary portion of the device,

Fig. 12 is a detailed view of portions of the mechanism shown in Fig. 11,

Fig. 13 is an enlarged sectional view through a fragmentary portion of the device.

In carrying out my invention, I provide supporting corner posts 1, connected adjacent their tops by longitudinal frame members 4, 5, and 6 and by cross end frame members 13, 106, and 127, as best seen in Figs. 2, 3, and 4 of the accompanying drawings. It will be noted that the members 4 and 5 are partly disposed within recesses 3 which are provided in the inner side of the corner posts 1 adjacent their tops. Additional posts 2 are located approximately midway between the corner posts 1, as shown, being connected with the end frame members 13, 106, and 127, as shown. In addition longitudinally extending members 7, 8, 9, and 10 connect the central posts 2 adjacent their upper ends. I also provide additional supporting posts 14 and additional cross braces 15. It will be noted that the longitudinal frame members 7 and 8 are partly disposed within recesses 11 and 12 in the sides of the central posts 2 (see Fig. 4). A plate 17 may be secured to the central posts 2, as shown, for a purpose which will be hereinafter set forth.

The parts described so far constitute the supporting structure of the device and may vary considerably from the forms pictured in the accompanying drawings, since it is only essential to my invention that a frame having the general characteristics of that illustrated be provided.

It is to be observed that the provision of central supporting posts and certain frame members divides the frame into two horizontally aligned compartments 128 and 129. A plate 16, which rests upon the inwardly projecting portions of the frame members 4 and 7, forms a bottom for the compartment 128. Horizontally disposed side frame members 18 surmount the frame members 6 and are connected by end members

19 which are supported by the frame members 13 and 127. A central member 20 surrounds the central frame member 10, as best seen in Fig. 4.

5 A table 21, which is movable in a vertical plane, is supported by the inwardly projecting portions of the frame members 6 and 10. Channel irons 22 may be provided around the edges of the table 21.

10 A shaft 23, journaled in the bearing 26 and a bracket 35, extends within the compartment 128. A bevel gear 27, which is rigidly secured to the shaft 23, is in mesh with a horizontally disposed pinion 28. The 15 latter is rigidly mounted upon a stub shaft 29, which has its ends journaled in the brackets 30 and 31. The brackets 30 and 31 are bolted at 37 to the wing portions 33 and 34 of a casing whose central or body portion 20 32 is positioned beneath the pinion 28. The wing portions 33 and 34 of the casing are secured to the bottom plate 16 by means of bolts 36. The wing portions 30 and 31 are formed with guideways 42 and 43 in which 25 racks 39 and 41 are slidably disposed. The rack 39 has teeth 38 in its side edge adjacent its inner end, which are in mesh with the teeth of the pinion 28. Likewise, the rack 41 has teeth 40 in its side edge adjacent its inner end, which are in mesh with the teeth of the pinion 28 at a diametrically opposite point to that at which the latter is engaged by the teeth 38 of the rack 39. Consequently, the racks 39 and 41 will be simultaneously moved an equal distance in opposite directions when the pinion 28 is being rotated. Teeth 44 are provided in the rack 39 in its upper side, while similar teeth 45 are provided in the upper side of the rack 40 41. The teeth 44 engage the teeth of a gear segment 46, which is rigidly mounted upon a countershaft 48. The countershaft 48 extends substantially the length of the compartment 128 and is journaled in brackets 45 50 (see Fig. 1), which are secured to the bottom plate 16 by means of bolts 51. In a like manner, the teeth 45 of the rack 41 engage the teeth of the gear segment 47, which is rigidly mounted on a countershaft 49. 50 The latter extends parallel to the countershaft 48 and is also journaled in the brackets 50, as shown. A plurality of cam members 52 are rigidly secured to the countershaft 48, being spaced therealong. Spaced 55 apart cam members 53 are rigidly secured to the countershaft 49. It is to be noted that the gear segments 46 and 47 are moved an equal distance in opposite directions by the operation of the shaft 23, which may be accomplished by operating a crank arm 24. The latter is secured to the end of the shaft 23 by means of a nut 25. The cam members 52 and 53, being positioned as shown in Fig. 60 11, will press upwardly against table rests 54, which are secured to the under surface of

the table 21. When the shaft 23 is rotated, the cam members 52 and 53 will be operated simultaneously to occasion an even upward movement of all parts of the table 21. A handle 55, which is adapted to be grasped 70 by the hand, may be secured to the arm 24 for convenience in operating the latter.

Referring now particularly to Figs. 1, 2, and 3, it will be noted that a plate 56 is embedded in the upper surface of the end 75 frame members 19, being secured thereon by means of bolts or screws 57. A central slot 58, which is adapted to receive the web of an I-beam 65, extends through each plate 56 and end frame member 19 substantially the 80 entire length thereof. The base of each I-beam 65 is rigidly secured to a member 64, which has downwardly extending arms 63, as best seen in Fig. 3. Wheels 61 are mounted on shafts 62. The latter have their ends 85 journaled in the arms 63. The grooved peripheral rim of each wheel 61 engages a rail 60 which is formed integrally with or rigidly secured to a plate 59. The upper portions of the I-beams 65 are rigidly secured 90 to plates 66. The latter are secured to and support a form which will be described in detail hereinafter. This form is supported at each end of the device in the manner described. Consequently, the plate holding 95 form may be moved substantially the width of the device.

The plate holding form or frame, which is substantially rectangular, is made of a continuous angle member 67. Reinforcing bars 100 68 are secured to the side portions of the frame. Members 69 and 72, which have the section of an inverted T-bar, are disposed parallel to the end portions of the member 67 at spaced distances therefrom. The member 69 has end portions 70 bent at right angles to the direction of its main portion, such end portions being secured to the side portions of the members 67 by means of bolts 71. Likewise, the member 72 is formed 110 with end portions 73, which are secured to the side portions of the member 67 by means of bolts 74. A slide member 75 is positioned adjacent the member 72, being supported upon the inwardly extending legs 115 of the side portions of the member 67. Coil springs 76, which have one end secured to the end portion of the angle member 67 by means of a pin 77, have their other end secured to pins 78 which extend through the 120 member 72 and are secured to the member 75 by means of screws 79. The coil springs 76 tend to normally prevent movement of the member 75 away from the member 72. The member 75 is rigidly secured to a spacing member 80, which is formed with a tongue 81 adapted to enter a groove 82, which is formed in one edge of each of a plurality of plates 83. The member 69 is also rigidly secured to a spacing member 130

84, which is formed with a tongue 85 adapted to enter a groove 86, which is provided in the opposite side edge of each of the plates 83.

5 Referring now to Figs. 1, 5, 6 and 9, it will be noted that each of the plates 83 is provided with handles 84 for convenience in placing the plates within the form. Each plate is provided with marginal plates 85, 10 which have openings 86 formed therethrough. The plates 83, when in position on the form, rest upon the inwardly extending horizontally disposed legs of the side portions of the angle member 67. A plurality of stud bolts 87 are spaced along the side portions of the angle member 67, projecting upwardly from the inwardly extending leg thereof. The plates 83 are placed 15 in position, the head 89 of the stud bolt 87 being inserted through the openings 86. Each plate is then moved toward the member 69. Each stud bolt 87 will move to the end of a narrow passage 88 which connects 20 with each opening 86, the plate thus being 25 locked in position.

To further clamp the plates together, I provide crank arms 90, which are secured to the ends of rods 91. The latter are screwed into threaded bores 92 of similar casings 93, which are secured between the members 72 and the adjacent end portion of the angle member 67, as best seen in Fig. 5. It will be noted that bolts 94 secure the casings 93 in position. Each rod 91 is formed 35 with an enlarged end portion 95 which has a central bore 96 in which a pin 97 is slidably received. Each pin 97 is secured to the member 75 by means of a screw 98. Consequently, when the rod 91 is screwed 40 into the casing, the member 75 will be moved in the direction of the member 69, moving the plates 83, which are disposed therebetween and securely clamping the same in 45 position. Each of the plates 83, which have a body portion preferably formed of wood, are provided with raised patterns indicated in general at 99. The latter are formed by bending angle shaped members as desired. Each angle member has a leg 100 positioned 50 at right angles to the body portion of the plate. The other leg 101 has angular indentations 102, which render the same flexible, thereby permitting the angle member to be bent into any desired shape to outline various patterns. Such patterns are then placed upon the surface of the plate 83 by 55 fastening the indented leg to the same by pins or screws (not shown).

Between the plate holding form and the 60 table 21, I provide a roller 107, which is positioned to engage the pattern outlining members when the plate holding form is moved across the device. The roller 107 is mounted upon the shaft 108, which has its 65 ends journaled in brackets 109. The latter

are secured to the end frame members 19, as shown. It will be noted that the roller 107 is disposed in a semi-cylindrical trough or well 104, which is supported and closed at its ends by plates 105. The latter are secured to the end frame members 127. A crank arm 110 is connected with one end of the shaft 108 to provide a means for rotating the roller 107, thereby keeping the surface of the same saturated with ink which is 70 contained in the semi-cylindrical trough 104.

From the foregoing description of the various parts of the device, the operation thereof may be readily understood. A handle 111 (see Fig. 1) is secured to one of 80 the reinforcing plates 68 and provides a means for moving the plate holding form into position to be engaged by the movable table 21 when the latter is raised vertically. When the plate holding form is being moved 85 across the machine, the roller 107 will contact with the face of the pattern outlining members, effectually inking the same. Cloth or the like is arranged in position on the movable table 21, which is then raised by 90 operating the crank arm 24 until the pattern is impressed on the cloth.

In order to insure the pattern being accurately marked upon the cloth, it is necessary that suitable means be provided for holding 95 the plate holding form in position relative to the movable table 21. To this end, the plates 66 are formed with extensions 112. A vertically extending casing 113, having a central bore 114 (see Figs. 5 and 13), is 100 mounted upon the extension 112, being rigidly secured thereon. A plug 115 screws into the upper end of the bore 114, and is provided with a central opening adapted to slidably receive a stem 116. The latter carries 105 a handle 117 at its upper end and has an enlarged lower end 118, which is inserted through an opening 120, in the extension 112 and which is adapted to enter a socket 119 when the plate holding form is in a desired 110 position with respect to the movable table 21. A spring 121 is mounted upon the stem 116 and normally holds the latter in the position pictured in Fig. 13. A set screw 123 has a projecting end arranged to enter a 115 vertically extending slot 124, which is provided in the stem 116. The stem 116 may therefore be raised when the handle 117 is grasped by hand, thereby allowing the plate holding form to be returned to its original 120 position as pictured in Fig. 1. It will be understood that the socket 119 is embedded in the frame member 19 in position with respect to the movable table 21 to insure proper contact of the cloth held on the same 125 with the pattern marking members of the plates 83 when the stem 116 is in the position pictured in Fig. 13 and the movable table 21 has been raised.

I ordinarily place a set of four of the 130

plates 83 in position on the plate holding form, thus providing patterns for a complete suit of clothing. When a desired pattern has been marked on cloth by operating my device, the marked cloth is placed upon additional layers of cloth and as many duplicate portions of a suit provided by one cutting operation as there are layers of cloth. The marking machine is again operated and the complete operation repeated. A number of stock patterns may be available at all times, the additional plates being stored in racks which are provided by securing angle irons 125 to the supports 14, as shown in Fig. 2.

Many modifications and adaptations of the form of the device pictured in the accompanying drawings may be provided without departing from the spirit and scope of the invention as set forth in the foregoing disclosure and outlined with greater particularity in the appended claims. I therefore consider such modifications and adaptations as my own.

It will be noted that the plate 17 forms a back for the above mentioned racks and protects the same from dust, chalk, and the like.

A line board 130 (see Fig. 4) is positioned along the edge of the central member 20 to limit the work which is placed on the movable table 21.

I claim:

1. A marking machine comprising a supporting frame, a work supporting table movable vertically, a plate holding form normally positioned in a higher horizontal plane than that of the work supporting table and to one side thereof, said plate supporting form being movable horizontally into a position directly above said work supporting table, a plate held by said plate holding form, said plate being provided with a pattern forming member secured to its under surface, an ink trough mounted in the frame between said plate holding form and said work supporting table, an inking member

disposed in said trough and having a portion arranged to contact with said pattern forming member when said plate holding form is moved horizontally thereacross, and means 50 for moving said work supporting table upwardly at will into contact with the pattern forming member to occasion the outline of the pattern being impressed upon the work.

2. A marking machine comprising a supporting frame, a work supporting table movable vertically, a plate holding form normally positioned in a higher horizontal plane than that of the work supporting table and to one side thereof, said plate supporting form being movable horizontally into a position directly above said work supporting table, a plurality of plates held by said plate holding form, each plate being provided with a pattern forming member secured to 60 its under surface, an inking member arranged to engage the pattern forming member when the plate holding form is being moved horizontally into a position directly above said work supporting table, thereby 65 occasioning the inking of the pattern forming member, means for locking said plate holding form in a position directly above said work supporting table, and means for moving said work supporting table upwardly at will into contact with the pattern forming member to occasion the outline of the pattern being impressed upon the work.

3. In a marking machine, a plate having a substantially rectangular body portion, a handle secured to the upper surface thereof to provide a means for moving the plate, and an angular member bent to form a desired pattern and having one leg rigidly secured to the under surface of the body portion, the other leg of the angle member depending therefrom, said angle member having its first mentioned leg indented to render the angle member flexible, thus permitting 85 a variety of patterns to be formed at will.

CHARLES EMIL LARSEN.
